UNITED STATES PATENT OFFICE

2,446,842

RAIL ANCHOR

Richard J. McComb, Chicago, Ill.

Application June 14, 1946, Serial No. 676,688

1 Claim. (Cl. 238—327)

1

Rail anchors, or anti-creepers, are intended to prevent the creeping of the rail in the track under traffic. As heretofore made in "one piece," they engage the base of the rail with a clamping action or grip that is intended to be increased as the tendency of the rail to creep forces a depending portion of the anchor against a crosstie. (Railway Engineering and Maintenance Cyclo-pedia, 1942, pp. 261-268.)

But this desirable result is not attained unless the anchor is applied to the rail in the correct relation to the direction of creep and to a tie, which is frequently not done in practice.

The principal object of this invention is to so improve such anchors that they will inherently function as intended when the rail creeps or tends to creep, whether applied as they are designed to be or the reverse.

The preferred embodiment of the invention is shown in the accompanying drawings, in which

Fig. 1 is a plan view of a fragment of a track with one of the anchors applied to the rail;

Fig. 2 is an enlarged cross section taken on the line 2—2 of Fig. 1;

Fig. 3 is an enlarged elevation of a fragment; and

Fig. 4 is a diagram illustrating the forces brought into play by the operation of the rail.

In these drawings, 10 indicates a portion of a crosstie fitted with a tie plate under a rail 12, the rail and the tie plate being fastened to the tie by spikes 13 in the familiar way.

The preferred form of the rail anchor best shown in Figs. 2 and 3 is made from high carbon or alloy steel rolled to special or "commercial" sections to suit the conditions. In this instance, it is shown as made from a bar $\frac{5}{8}$ " thick by $1\frac{7}{16}$ " wide, forged or bent to the configuration best shown in Fig. 2. This gives the anchor two hooks, generally indicated by 14 and 15, for receiving and clamping the opposite sides of the rail base 16. Each of these hooks blends into a reverse bend 17, which in turn blends into a larger bend forming a bow 18, which serves as a lever by which the creeping force is transferred from the rail anchor to an adjacent crosstie, and thence to the ballast.

In this illustration, an A. R. E. A. 112-pound rail is shown, and by the standard the outer corners of the base, at 19, are rounded on a radius of $\frac{1}{16}$ "; and, in order to provide a good biting or clamping action between the upper jaws 20 and 21 of the hooks 14 and 15, the adjacent surface of each jaw is substantially tangent to that curved corner at or adjacent to its juncture with the

2

plane upper surface 9 of the rail base, whereby the corners of the jaws form teeth which readily bite into and firmly engage the corresponding rounded corners of the rail base.

5 The curved portions 22 and 23 on the opposite jaws 24 and 25 form a somewhat similar engaging teeth arrangement to which the lower surface 26 of the rail base is tangent.

The lever arm 18, forming the intermediate 10 and depending portion of the rail anchor, is provided with oppositely disposed and centrally located projections or feet 28 for contact with the adjacent side of tie 10 when the rail anchor is in use. These may be produced in a variety of 15 ways—for example, the $\frac{5}{8}$ " stock may be forged or swaged to $\frac{1}{8}$ " in that area to produce the projections and also to reduce the thickness of the bar, thereby to give it better yield during the operation of applying the anchor to the rail.

Another expedient would be to groove the intermediate portion at the bottom, as indicated at 29 (Fig. 3) to thereby force the metal laterally in that figure and form the feet 28. This also has the advantage of improving the spring action in applying the anchor to the rail. However 20 the feet are formed, it is important that they be centered with respect to the grip of the jaws on the rail base to the end that there will be no twisting or slewing that would tend to release the gripping or binding action of the jaws. As here illustrated, the feet 28 are made to extend in opposite directions along the area bounded by the reference numerals 30 in Fig. 2.

Turning now to Fig. 3 and assuming that the 35 creep is in the direction to the left, as indicated by the arrow on the rail 12, it will be seen that any creep or tendency to creep will bring the left foot 28 against the side of the adjacent tie 10, the reaction from which will cause the jaws of the 40 hooks 14 and 15 to securely grip the side portions of the rail base and hold it against any creep, or at least make a resistance to any creep to the extent that the tie is held by the ballast.

In Fig. 4, the forces are illustrated in diagram 45 in which the arrow 32 indicates the pressure of the foot 28 against the tie 10. The arrow 33 indicates the upwardly and backwardly directed force of the lower jaws against the bottom of the rail base at 22 and 23, and 34 indicates the 50 force of the upper jaws of the hooks 14 and 15 against the outer rounded corners of the rail base at 19.

The dotted arrow 35 in Fig. 4 indicates a 55 reverse arrangement in which the creep is to the right in that figure, and the foot 28 at the right

is resting against a tie 10 at the right. The reaction through the anchor in such an instance would be the reverse of that shown in solid lines, but the binding or gripping action on the rail would be the same.

It should thus be evident that no matter how thoughtlessly or carelessly rail anchors embodying this invention are applied to the rail, they will function for the intended purpose if they are adjacent to a tie in the direction of the creep. This represents an important improvement over all rail anchors heretofore available, and the important feature of the improvement is it comprises the projections or feet 28 oppositely directed and centrally located so that there is unavoidably a proper contact between the lower end of the lever arm 18 and the tie to effect the binding or gripping action of the hooks or other devices in the rail anchor with the rail base.

This improvement is not limited to the particular forms of hooks and jaws here disclosed, but is applicable to many forms of rail anchor heretofore and now available. The hooks and jaws here illustrated were chosen because they are the preferred form. But that choice was not intended to impose a limitation on the claim.

The jaw 21 has an upwardly inclined terminal portion 40 for cooperation with the special tool as the anchors are being applied to the rail, and the jaw 15 has a differently directed terminal 41 for cooperation with the tool as the anchors are removed from the rail. The shape and direction of the terminals 40 and 41 are suitable to the particular form of hooks designed for use with 112-pound A. R. E. A. rail. Variations in those will be made to suit other conditions.

From Fig. 3, it will appear clearly that the presence of projections or feet 28 insures that the lever arm will clear the tie plate, even though it should overhang the side of the tie. This is an important advantage because, if the lever should come against the tie plate, as frequently

happens with prior rail anchors, the leverage is so short as to give no substantial anchorage to the rail.

I claim:

- 5 A rail anchor substantially symmetrical along its longitudinal center line and having spaced rail base jaws for gripping the rail base at each side, a depending lever portion connecting said jaws for forcing the latter into gripping engagement with the rail base, said jaws and said lever portion being formed from stock of substantially uniform cross section, the central part of said lever portion below said rail base being deformed along the top and bottom thereof to provide 10 smoothly curved projections extending laterally in opposite directions beyond the side walls of said anchor whereby one of said projections may contact the side of a tie upon creeping of the rail and further providing upper and lower 15 grooves thereby reducing the effective cross section of said central part in the vertical plane adjacent said projections to improve the spring action.

RICHARD J. McCOMB.
